UNITED STATES PATENT OFFICE.

ROBERT W. EMERICK, OF HOMESTEAD PARK, PENNSYLVANIA.

MILK BOTTLE.

Application filed October 13, 1925. Serial No. 62,296.

The present invention relates to receptacles such as are intended for repeated use, and has reference more specifically to bottles such as are used for the vending and transporting of milk, cream, and similar liquids, and which class of bottles are generally closed at their mouths by means of a disc shaped paste-board cap.

In the present form of milk bottles intended for repeated use, an annular flange is formed in the neck of the bottle so as to form a seat for the usual paste-board cap which is used for closing the bottle. This abrupt annular flange forms a pocket or shelf allowing sediment and contaminated matter to gather about the flange for the breeding of germs which become mixed with the milk when next being poured from the bottle. This flange also prevents proper and thorough cleansing of the bottle when again desiring to use the same, due to the inability of being able to thoroughly remove the contaminated matter from the abrupt angular pocket formed by the annular flange.

It is therefore a primary object of this invention to provide an improved bottle for repeated use in the vending of milk, cream, and similar liquids, embodying sanitary features whereby foreign and contaminated matter will be prevented from forming in the neck of the bottle.

A further object of the invention is to provide an improved milk bottle having the mouth thereof so formed as to permit of the use of the usual standard size card-board cap, and with the seat for the cap so formed as to permit of ready and thorough cleaning of the mouth of the bottle.

A still further embodiment of the invention is in so forming the seat for the cap, as to permit of the liquid in the bottle to readily drain back into the bottle and not become lodged on an abrupt annular flange such as is apparent with the present types of milk bottles employing a disc shaped cap for seating upon the annular flange formed in the neck of the bottle.

A still further object of the invention resides in the provision of an improved milk bottle embodying the aforementioned features, wherein the construction of the bottle is such as to permit of its being manufactured with machines now in common use for the making of milk bottles, and in which

machines the necks of the bottles are shaped by a plunger which is inserted and withdrawn from the neck of the bottle.

Other objects and advantages of the invention will be apparent during the course of the following detailed description, taken in connection with the accompanying drawing forming a part of this specification, and in which drawing:

Fig. 1 is a view of a milk bottle showing the upper portion thereof in central vertical section and constructed in accordance with my invention, and showing the customary disc shaped cap in position for closing of the bottle.

Fig. 2 is a top plan view of a milk bottle constructed in accordance with my invention.

Fig. 3 is a transverse section on line 3—3 of Figure 1, looking in the direction of the arrows; and,

Fig. 4 is an enlarged vertical fragmentary sectional view of the upper portion of the bottle and illustrating more clearly certain details of construction of the neck of the bottle.

Referring to the drawing in detail, and wherein similar reference characters designate corresponding parts throughout the several views; 5 designates generally a milk bottle of usual appearance and formation externally, having a reduced neck portion 6, the upper end or mouth of which is provided with the usual enlarged external rim 7 having a flattened top or end face 8. This neck portion 6 is formed with its least internal diameter at a point substantially midway the length of the neck as designated at X, and from which point the internal surface of the neck flares or tapers outwardly both toward the mouth or end face 8 as at 9, and toward the main body portion of the bottle as at 10.

Formed on the inner surface of the neck 6 and preferably spaced equidistant apart, are a plurality of inwardly extending polygonal shaped ribs 11 having their major axes extending in longitudinal relation to the neck, and with the confronting inner faces 12 thereof disposed in parallel relation to one another as clearly illustrated in Figure 1. These lugs or ribs 11, which are substantially triangular shape in formation, merge at their lower ends into the inner sur-

face of the neck 6 at a point of its least internal diameter X, and extend upwardly with their inner faces 12 in parallel relation to the axis of the neck, to a point spaced below the end face 8, in a manner so that a slight shoulder 13 is formed at the upper end of each rib, and which shoulders provide a stop for the disc shaped cap 14 when inserted into the mouth of the bottle. It will here be further stated, that the ribs 11 which extend upwardly from a point constituting the least internal diameter of the neck, and which ribs are disposed wholly within area of the upwardly flaring portion 9, have their inner confronting faces 12 spaced apart at their upper ends, a distance equal to the internal diameter of the neck at the point X. Thus it will be seen that a plunger for shaping the neck with such ribs 20 may be readily inserted and withdrawn from the neck, since the internal formation of the neck at all points above the point X is of either equal or greater diameter from the point X upwardly to the end face 8. These 25 spaced apart ribs, and as is readily apparent, allows for the inner surface of the neck to be continued in an unbroken line between the ribs to the extreme upper end of the neck, thus allowing the liquid to readily and 30 quickly drain back into the bottle unrestrained.

It can be readily seen that by so providing a plurality of these spaced apart ribs about the inner surface of the neck 6, that an 35 effective stop or seat will be provided for the usual cardboard cap 14 and by merging all portions of the ribs into the surface of the neck in arcuate shaped fillets, no abrupt angular pockets or shelves will be formed for 40 retaining foreign matter and contaminating the liquid in the bottle. A bottle so constructed, will permit of the neck being readily and thoroughly cleaned, since a brush or other cleaning device will readily remove 45 any sediment which may have collected about the ribs. It will also be apparent that with a milk bottle so constructed, the disc shaped cap may be easily removed by merely slipping a knife blade or similar flat article into 50 the mouth of the bottle between two of the lugs, since the inner surface of the neck con-

tinues unbroken between each two adjacent ribs.

From the foregoing description of this invention it will be apparent that a novel and 55 efficient milk bottle has been provided embodying desirable sanitary features without altering the general external appearance and shape of the bottle, and embodying features whereby bottles so constructed, may be manufactured with the equipment now in common use for producing milk bottles.

Various minor changes may be made to the form of the invention herein shown and described, without departing from the spirit 60 of the invention or the scope of the claims.

I claim:

1. A bottle of the character described, embodying a neck portion having its least internal diameter at a point spaced below the 70 mouth of the bottle, and a plurality of spaced apart ribs extending upwardly from the point of least internal diameter of the neck and terminating short of the mouth of the bottle, with the diametrical distance between the confronting faces of the ribs at their upper portions at least equal to the dimension of the least internal diameter of the neck.

2. In a milk bottle having a conventional 80 milk bottle body and a conventionally shaped milk bottle neck, said milk bottle neck at the inner periphery of the opening thereof having spaced projections, said projections being below the top edge of the neck and constituting the sole bearing support for the 85 milk bottle cap in its sealing position.

3. In a milk bottle having a conventional milk bottle body and a conventionally shaped milk bottle neck having a relatively large 90 opening upwardly flaring with an increasing diameter, said neck in the flaring opening thereof at the inner periphery thereof having spaced projections providing cap supporting shoulders having rounded fillet 95 junctures with the inner surface of the neck and from said shoulders merging into the material of the neck at the restricted part of the opening without the forming of under shoulders facing into the milk bottle body.

ROBERT W. EMERICK.
